[57] CLAIM

The ornamental design for the outsole, as shown and described.

DESCRIPTION

FIG. 1 is a perspective view of an outsole showing our new design, the broken lines showing recessed areas in FIGS. 1 and 3 being for illustrative purposes only and forming no part of the claimed design;

FIG. 2 is a bottom plan view thereof; the broken lines showing a logo and label being for illustrative purposes only and also forming no part of the claimed design;

FIG. 3 is a top plan view thereof;

FIG. 4 is a left side elevational view thereof;

FIG. 5 is a right side elevational view thereof;

FIG. 6 is a front elevational view thereof; and,

FIG. 7 is a rear elevational view thereof.
